UNITED STATES PATENT OFFICE.

ROBERT R. ROBERTS, OF WASHINGTON, DISTRICT OF COLUMBIA.

CANE-MILL.

SPECIFICATION forming part of Letters Patent No. 639,436, dated December 19, 1899.

Application filed March 13, 1899. Serial No. 708,885. (No model.)

To all whom it may concern:

Be it known that I, ROBERT R. ROBERTS, a citizen of the United States, residing at Washington, in the District of Columbia, have invented certain new and useful Improvements 5 in Cane-Mills, of which the following is a specification, reference being had therein to the accompanying drawings.

This invention relates to cane-mills, and is 10 particularly adapted for the extraction of saccharine juices from sugar and similar canes.

The invention has for its object to provide 15 a series of rolls in feeding relation to each other and so arranged that the first pair thereof will slit the cane, after which the second pair of rolls compresses or breaks the cells transversely of the cane, and the final rolls are adapted to completely compress and crush 20 the cells within the cane, and thus extract the juice therefrom.

The invention has for a further object to 25 provide improved feeding means for introducing the cane in proper alinement with the slitting devices or rolls and also improved scrapers and deflecting devices for preventing 30 the adherence of the cane to the surfaces of the rolls.

Other objects and advantages of the invention 35 will hereinafter appear in the following description, and the novel features thereof will be particularly pointed out in the appended claims.

In the drawings, Figure 1 is a longitudinal 40 vertical section through the invention. Fig. 35 2 is a plan thereof with parts broken away. Fig. 3 is a detail of the spring tension for the rolls, and Fig. 4 is a detail perspective of the guiding-plate for introducing the cane.

Like letters of reference indicate like parts 45 throughout the several figures of the drawings.

The letter A designates a framework, which 50 may be of any desired dimensions or configuration and is usually composed of opposite members secured together in an ordinary manner—for instance, by tie-bolts A'. This frame is also provided with vertically-extending standards A², within which bearings for the several rollers of the mill may be provided, and these standards are connected together by a longitudinal web A³, as shown in Fig. 1. This particular construction of sup-

porting-frame, however, is immaterial and may be changed at will.

Within the frame three sets or pairs of rolls 55 are supported in feeding relation to each other—that is, the slitting-rolls B, the breaking or compressing rolls C, and the crushing-rolls D. Each of the slitting-rolls is provided with a series of peripheral parallel cutting edges or knives B', the knives upon one roll being located between two adjacent knives upon the opposite roll, so as to travel in the way or groove formed by the adjacent knives. The breaking or compressing rolls 60 C are each provided with a series of longitudinal ribs C', which ribs intermesh with each other, as shown in Fig. 1, while the crushing-rolls D are provided with plane peripheries adapted to completely crush the cane, and 65 thus extract the juice therefrom, leaving the bagasse or fiber in a dry condition. The upper roll of each set is mounted in a guide A⁴, formed in the standards A², and above the bearing-block A⁵ of the roll a tension spring 70 A⁶ is interposed, while within this spring a rubber or elastic block A⁷ is located and adapted to limit the extent of compression imparted to the spring. The tension of the roll may be governed and adjusted by means 75 of a suitable set-screw A⁸, bearing upon a pressure-plate A⁹, located above and upon both the spring A⁶ and elastic block A⁷. This construction permits one of the rollers to yield when for any reason a hard substance, 80 such as a stone or other matter not intended to be introduced into the machine, comes into contact with the rolls. This yielding of the roll prevents injury to the surface or periphery thereof, which would otherwise occur, 85 and the tension of the roll in relation to its opposite member can be regulated to any extent desired.

Beneath the rolls a receiving-trough E is located and adapted to retain the juice extracted 90 from the cane, which may be withdrawn therefrom through a suitable spout E', while the cane is led to the mill upon any desired form of carrier—for instance, a belt E², traveling over rollers E³. The bagasse may 95 be removed from the mill by a similar belt or conveyer E⁴, if desired, which is carried upon suitable rollers E⁵, mounted in the frame of the machine, and is provided with the scraper

or doctor blade E⁶, supported in any desired manner—for instance, by a connection E⁷ to the trough E. Between the series of rolls gratings F are secured or retained by means 5 of flanges or brackets F', carried by the opposite walls of the frame and upon which the grates rest and are held by gravity. The edges of these grates adjacent to the rolls may be beveled, if desired, as shown at F², in 10 order to fit more closely the curvature of the roll, and thus receive from the roll the cane.

It has been found very desirable to use in connection with the rollers, particularly the slitting-rolls, scrapers to remove from the rolls 15 the adhering cane. In Fig. 1 a scraping and deflecting blade G has been illustrated, which is provided with a series of teeth G', adapted to fit or intermesh between the knives B' of the upper roll B, and said scraper is pivotally 20 mounted at G³, so as to be adjusted to and from the roll. The scraper can be secured in its adjusted position by means of a slot G³ in the frame A³ and a suitable clamping nut or bolt G⁴. It will be observed that any cane removed 25 from the upper roll D will come into contact with the deflecting-face G⁵ and be thus directed downward upon the grating F and in position for introduction into the next pair of rolls. The lower roll B is provided 30 with an adjustable scraper H, provided with a toothed blade H' and adapted to be adjusted in slots H², formed in a part of the frame. This scraper is mounted and slides upon the grate F, so that any cane removed 35 from the roll rides over the scraper-blade.

For the purpose of preventing adhesion of 40 and guiding and deflecting the cane after its passage between the breaking or compressing rolls, a feed-roller I is provided and mounted somewhat closely to the upper breaking-rolls 45 upon a shaft I', the bearings of which are under spring tension, as shown by dotted lines at I² in Fig. 1, so as to hold this roll in contact with the grate adjacent to the delivery-face of the breaking-rolls. The face of the 50 roll I is provided with an elastic covering I³, of rubber or other suitable material, and the tension of the spring I² may be adjusted, when desired, by means of a suitable set-screw I⁴, mounted in the frame A³ of the mill. This roll 55 is driven by a suitable connection—for instance, a sprocket-chain I⁵, extending from a suitable sprocket I⁶ upon the shaft of the rolls D to a corresponding sprocket I⁷ upon the shaft I' of the roller I. It will be obvious 60 that the diameter of these sprockets may be varied to regulate the speed of rotation imparted to the roller I (which must be equal to or greater than that of the rolls C) and the consequent feed of material effected by 65 said roll. In order to properly feed the material or cane to the slitting-rolls, a guide-plate J is secured to the frame and provided with a series of flanges I', between adjacent ones of which the cane passes and is thus brought into proper position to be longitudinally slitted and can always be presented in

substantially the plane of the cutters or knives B' upon said slitting-rolls. Above the guide-plate J a guard or shield J² is provided, which prevents the entrance of more than one layer of cane between the rolls B. The cane frequently becomes piled up or superposed one above another and would in this condition feed irregularly to the rolls. 75 The guard - plate J² prevents this; and in connection therewith there is a pivotally-mounted plate K for pushing back the cane which may collect in front of the same, so that the cane may be fed under the guard- 80 plate when an opportunity presents. This pusher-plate K may be operated in any desired manner, either by the handle K' or automatically by means of a cam K², acting upon the end of a rod K³, which rod is 85 normally held in the position shown in Fig. 1 by means of a spring K⁴, one end of which is connected to the rod K³ and forms an abutment in the compression of said spring. The rotation of the cam K² will intermittently 90 actuate the pusher-plate K to remove such cane as may collect in front of said plate, and thus automatically regulate the feed of the mill without the constant attention of an operator to regulate the feed of the cane upon 95 the carrier E².

The several rolls of the series may be driven by any desired gearing, an instance of which is here shown, comprising finger-gears L upon each roll of the several pairs intermeshing 100 with each other, so as to permit the separation of the rolls to a limited extent without effecting the driving thereof. The main driving power may be applied to a band-wheel L upon the lower roll B, and the power from 105 the rolls B to the rolls C is transmitted through an intermediate finger-gear L², pivotally journaled in a slot L³ for the purpose of adjustment. Power is transmitted from the rolls C to the final crushing-rolls D by means of a 110 finger-gear L⁴, meshing with the gears carried upon the shafts of the lower rolls C and D. Provision is also made to replace the gear L⁴ with a gear of different size when it is desired to drive either the rolls C or D at 115 a different speed than originally geared—for instance, to quicken the speed of the rolls D, and thus produce a drawing action upon the cane in its passage between the rolls C. For this purpose a journaling-slot L⁵ is provided, so that the pivotal center of the meshing gear may be changed to correspond with a different gear carried upon the shaft D' of the lower roll D. I have indicated by dotted lines in Fig. 2 the location of a smaller gear 120 upon the shaft D' of the lower roll D and the introduction of a larger gear—that is, with a greater number of teeth—in place of the gear L⁴, as shown. As heretofore described, the power for the feeding-roll I is transmitted 125 from the upper shaft D' of the set. Furthermore, it will be observed that these several rolls are set on a declining angle of about thirty degrees; but this angle may be ad-

justed to any degree desired or found necessary in the character of work to be performed. The angle at which the rolls are set facilitates the feed, although in most instances the

5 rolls are located so closely adjacent that the cane is received by one roll before it completely leaves the roll which has previously acted thereon. The distances between the rolls, however, may be varied as found desirable in different classes of work.

The general operation of the mill will be apparent from the foregoing description, and attention need only be particularly called to the operation of the series of rolls which first 15 longitudinally slit the cane, thus exposing the cells constituting the interior tissue, which cells are next broken transversely by means of the corrugated rolls C, so that upon leaving said rolls the cellular structure is completely broken, so as to permit the free escape of the sap or juice from the canes before or during their passage between the crushing-rolls D. This compression is accomplished in a substantially automatic manner by reason 20 of the several devices heretofore described, and the mill can consequently be operated by less attendants, as the rolls are so located in feeding relation that after the introduction of the cane the expressing of the 25 juice is entirely accomplished without the attention of an employee. The several auxiliary devices described also materially assist in securing the particular efficiency and economy effected by the structure presented.

30 It is obvious that changes may be made in the details of construction and configuration of the several parts without departing from the spirit of this invention as defined by the appended claims.

35 Having described my invention, what I claim as new, and desire to secure by Letters Patent, is—

1. In a cane-mill, the combination of three pairs of rolls arranged in feeding relation with each other, the first pair provided with circumferential slitting means, the second pair provided with longitudinal compressing ribs and grooves, and the third pair having plane peripheries, whereby the material is slit longitudinally, bent or crushed transversely and finally uniformly compressed in regular 45 succession; substantially as specified.

2. In a cane-mill, the combination of three pairs of rolls arranged in feeding relation with each other and in successively-depressed horizontal planes, the first pair provided with circumferential slitting means, the second pair provided with longitudinal compressing ribs and grooves, and the third pair having plane 55 peripheries, whereby the material is slit longitudinally, bent or crushed transversely and finally uniformly compressed in regular succession; substantially as specified.

3. In a cane-mill, the combination with a 60 pair of slitting-rolls, a pair of breaking and compressing rolls, and a pair of crushing-rolls, one member of each of which is yieldingly

mounted in relation to the cooperating member, said pairs of rolls being located in feeding relation with each other; substantially as 70 specified.

4. In a cane-mill, the combination with slitting-rolls, of a guide-plate provided with parallel partition-plates adapted to form channels or ways in alignment with the peripheral 75 slitting devices carried upon said rolls; substantially as specified.

5. In a cane-mill, the combination with slitting-rolls, of a guide-plate provided with parallel partition-plates adapted to form channels or ways in alignment with the peripheral 80 slitting devices, carried upon said rolls, and a guard-plate to prevent the introduction of a superposed layer of cane; substantially as specified.

6. In a cane-mill, the combination with slitting-rolls, of a guide-plate provided with projections adapted to introduce the cane in alignment with the slitting devices carried upon said rolls, and a pusher-plate adapted 90 to be moved and remove accumulated cane from the vicinity of the guide-plate; substantially as specified.

7. In a cane-mill, the combination with a 95 pair of rolls, of a pusher-plate located at the feeding side of said rolls, and a device rotatable with said rolls for intermittently actuating said pusher-plate to remove cane in contact therewith; substantially as specified.

8. In a cane-mill, the combination with a 100 pair of rolls, of a pusher-plate located at the feeding side of said rolls, a cam carried by the shaft of one of said rolls, and a spring-actuated rod connected to said pusher-plate against which rod said cam is adapted to operate; substantially as specified.

9. In a cane-mill, the combination with slitting-rolls having channels upon their surfaces, of a pivoted toothed scraper having a deflecting-face projecting upwardly and then 110 downwardly at an angle to the scraper-blade, and means for adjusting the scraper in its relation to the rolls; substantially as specified.

10. In a cane-mill, the combination with a 115 pair of longitudinally-corrugated rolls, of a clearing and feeding roll arranged closely to and at the delivery side of the upper member of said corrugated rolls for preventing the adhesion of cane thereto, a base-plate upon which said roll bears, a spring for holding 120 said roll in yielding contact with said plate and means for driving said clearing-roll in an opposite direction to that of said upper roll; substantially as specified.

11. In a cane-mill, the combination with a 125 pair of slitting-rolls, a pair of breaking-rolls and a pair of crushing-rolls, of a toothed scraper operating in the channels of one of said slitting-rolls, and means for holding and adjusting said scraper relatively to said roll; 130 substantially as specified.

12. In a cane-mill, the combination with a pair of slitting-rolls, a pair of breaking-rolls and a pair of crushing-rolls, of a spring-held

clearing and feeding roll held adjacent to said breaking-rolls and provided with an elastic periphery, means for adjusting the tension of the spring-support for said roll, and means for driving the same; substantially as specified.

13. In a cane-mill, the combination with a frame carrying a pair of slitting-rolls, a pair of breaking-rolls and a pair of crushing-rolls in feeding relation with each other, of brackets carried by said frame between said rolls, removable grating-plates located on said brackets and between said rolls, and a delivery-trough beneath said series of rolls; substantially as specified.

14. In a cane-mill, the combination with a pair of slitting-rolls, a pair of breaking-rolls and a pair of crushing-rolls, each provided with driving-gears, of an intermeshing gear and a spindle therefor removably and adjustably supported in a slotted frame to transmit power from one pair of said rolls to another; substantially as specified.

15. In a cane-mill, the combination with a pair of slitting-rolls, a pair of breaking-rolls, and a pair of crushing-rolls, of a bearing-block for one of each pair of said rolls, a spring interposed between said bearing-block and a fixed support, an elastic block within said spring, and a tension-screw adapted to bear upon said spring and elastic block; substantially as specified.

16. In a cane-mill, the combination of a pair of slitting-rolls, a pair of breaking-rolls, and a pair of crushing-rolls located in feeding relation and in descending horizontal planes, a guide-plate located at the feeding side of said slitting-rolls, scrapers operating at the delivery side of said slitting-rolls, a feed-roll located at the delivery side of said breaking-rolls, gratings between said several rolls, and means for driving said rolls simultaneously; substantially as specified.

17. In a cane-mill, the combination of a pair of slitting-rolls, a pair of breaking-rolls, and a pair of crushing-rolls located in feeding relation and in descending horizontal planes, a guide-plate located at the feeding side of said slitting-rolls, scrapers operating at the delivery side of said slitting-rolls, a feed-roll located at the delivery side of said breaking-rolls, gratings between said several rolls, means for driving said rolls simultaneously, a guard-plate above said guide-plate, a pusher-plate automatically operated in the rotation of said rolls, and yielding bearings for the upper roll of each pair of said series; substantially as specified.

In testimony whereof I affix my signature in presence of two witnesses.

ROBERT R. ROBERTS.
